(57) **CLAIM**

The ornamental design for a detector pen, as shown and described.

DESCRIPTION

FIG. 1 is front view of a first embodiment of a detector pen with our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is another perspective view thereof;

FIG. 9 is an enlarged top view thereof;

FIG. 10 is an enlarged bottom view thereof;

FIG. 11 is front view of a second embodiment of a detector pen with our new design;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a perspective view thereof;

FIG. 18 is another perspective view thereof;

FIG. 19 is an enlarged top view thereof; and,

FIG. 20 is an enlarged bottom view thereof.
